(57) CLAIM

The ornamental design for the table base, as shown and described.

DESCRIPTION

FIG. 1 is a perspective view of a table base comprising the new design;

FIG. 2 is a front elevational view thereof;

FIG. 3 is a top view thereof;

FIG. 4 is a left side elevational view thereof, the right side elevational view being a mirror image thereof; and,

FIG. 5 is a perspective view of a second embodiment of a table base shown broken away for indeterminate length which is the sole difference between it and FIGS. 1-4.

The broken lines are for illustrative purposes and forms no part of the claimed design.
